CLAIM

The ornamental design for a bicycle cover, as shown and described.

DESCRIPTION

FIG. 1 is a perspective view of a bicycle cover showing my new design, it being understood that the broken lines are for illustrative purposes only and forms no part of the claimed design;

FIG. 2 is a left side elevation view of the invention, the right side elevation view being a mirror image thereof;

FIG. 3 is a front elevational view of the invention;

FIG. 4 is a rear elevational view of the invention;

FIG. 5 is a top plan view of the invention; and,

FIG. 6 is a bottom plan view of the invention, illustrating the cover of the invention without the bicycle.
